(57) **CLAIM**

The ornamental design for a monitor, as shown and described.

DESCRIPTION

FIG. 1 is the perspective view of a monitor showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is the rear-side perspective view thereof; and,

FIG. 9 illustrates the monitor of FIG. 8 with the stand extended.

The broken lines depict portions of the monitor only and form no part of the claimed design.

The shade lines in the figures show contour and not surface ornamentation.
